(57) **CLAIM**

We claim the ornamental design for an architectural ceiling tile with a singular tile featuring three dimensional surface topography comprised of four semi-circular blades in a radial configuration, as shown and described.

DESCRIPTION

FIG. 1 is a perspective view of an architectural ceiling tile with a singular tile featuring three dimensional surface topography comprised of four semi-circular blades in a radial configuration, showing our new design.

FIG. 2 is a front view of an architectural ceiling tile with a singular tile featuring three dimensional surface topography comprised of four semi-circular blades in a radial configuration.

FIG. 3 is a back view of the architectural ceiling tile with a singular tile featuring three dimensional surface topography comprised of four semi-circular blades in a radial configuration.

FIG. 4 is a left side view of the architectural ceiling tile with a singular tile featuring three dimensional surface topography comprised of four semi-circular blades in a radial configuration.

FIG. 5 is a right side view of the architectural ceiling tile with a singular tile featuring three dimensional surface topography comprised of four semi-circular blades in a radial configuration.

FIG. 6 is a top view of the architectural ceiling tile with a singular tile featuring three dimensional surface topography comprised of four semi-circular blades in a radial configuration; and,

FIG. 7 is a bottom view of the architectural ceiling tile with a singular tile featuring three dimensional surface topography comprised of four semi-circular blades in a radial configuration.
